UNITED STATES PATENT OFFICE.

JOSEF SVARTZ, OF STOCKHOLM, SWEDEN.

MULTICYLINDER PLUNGER PUMP, COMPRESSOR, AND THE LIKE.

Application filed July 24, 1924, Serial No. 727,909, and in Sweden October 27, 1923.

The present invention relates to an improvement in such multi-cylinder plunger pumps, compressors and the like which are provided with means for the stepwise variation of the output of the pump or the like, consisting of one or more regulating members which are adjustable in different regulating positions in which—by the aid of cams or the like—they maintain the suction valves of certain cylinders permanently open so that said cylinders do not take part in the pumping. An arrangement of this type is described for instance in the U. S. Patent No. 1,468,176. In said prior arrangement the suction valves are under the influence of springs, and the suction valves which participate in the pumping, are opened by the suction of the corresponding plungers when these plungers begin their suction stroke. In order that the suction valves shall be opened immediately at the beginning of the suction stroke the springs actuating said valves must be made comparatively weak. The use of such weak springs entails, however, particularly at higher speeds of the plungers, the disadvantage that the suction valves do not become closed sufficiently rapidly at the end of the suction stroke, and it may therefore easily happen that a greater or less portion of the liquid passes back to the suction conduit at the beginning of the subsequent pressure stroke and is lost, so that the pump will not yield the exact output for which it has been adjusted.

The invention has for its purpose to avoid this disadvantage and consists principally in that the pump is provided, besides with the adjustable regulating member or members above referred to, with one or more governing members—for instance cams or the like—which are connected with the plungers in such manner that they are driven with a speed corresponding to the speed of said plungers and which members actuate those suction valves which are not maintained permanently open by the regulating members, so that said suction valves become positively opened at the beginning of the suction strokes of the corresponding plungers. The suction valves being thus opened positively, it becomes possible to let strong springs actuate the same to close said valves rapidly at the end of the suction strokes, so that no portion of the liquid drawn in is lost. In this manner the pump or the like will therefore, after each adjust-

ment of the regulating member, yield exactly the output for which it has been adjusted, and an exceedingly accurate regulation of such output is thus rendered possible.

In the accompanying drawing an embodiment of the invention is illustrated by way of example. Fig. 1 shows a vertical longitudinal section of a multi-cylinder plunger pump according to the invention, and Fig. 2 is a cross section on the line A—B in Fig. 1.

The pump illustrated in the drawing is provided with twelve cylinders 1—only one of which is shown in Fig. 1—which cylinders are arranged in two star-shaped groups in the embodiment illustrated, each group comprising six cylinders. The cylinders of the one group are located in the plane C—D, and the cylinders of the other group in the plane E—F in Fig. 1. The cylinders of the same group may, for instance, be displaced at 60 degrees with respect to each other, whilst the cylinders of the different groups are displaced 30 degrees with respect to one another, so that viewed from one end of the pump a cylinder of one group is located centrally in the space between two cylinders of the other group. In the inwardly open cylinders 1 single-acting pump plungers 2 are movable which are driven by means of piston rods 3 from two cranks 4 and 5 on the common crank shaft 6 in such manner that the six plungers 2 operating in the plane C—D are driven from the crank 4, whilst the six plungers operating in the plane E—F are driven from the crank 5. The two cranks 4 and 5 are displaced at 180 degrees with respect to each other in the embodiment illustrated. The crank shaft 6 is journalled in two ball bearings 7, one of which is located in one end wall 8 of the pump casing, and the other of which is located in a special detachable partition 9 within the pump. One end of the crank shaft projects outside the wall 8 and supports a pulley, a gear wheel or the like, not illustrated in the drawing, by means of which it may be rotated.

The outer closed ends of the cylinders 1 are in direct communication with suction and pressure chambers 10, one for each cylinder, said chambers being completely separated from one another. Those suction and pressure chambers 10 which are associated with the cylinders in the plane C—D—that is to say, every second chamber—are compara-

tively short, taken in the axial direction of the pump, whilst those suction and pressure chambers 10 which are associated with the cylinders in the plane E—F, form longer 5 passages which extend between the cylinders in the plane C—D and the first named chambers 10. Each chamber 10 is provided with a suction valve 11 which is actuated by a coil spring 12, and with a pressure valve 13 10 which is actuated by a coil spring 14, both of said springs tending to close the valves. The suction valves 11 of all twelve chambers 10 or all twelve cylinders 1, are located in the same plane, as will be seen from Fig. 2. 15 When said suction valves are opened the chambers 10 obtain communication with a larger common suction chamber 15 which is connected through a pipe connection 16 with the suction conduit which is not shown in 20 the drawing. The pressure conduit, not shown, extends from an annular passage 17 extending around the pump casing and with which the chambers 10 are put in communication when the pressure valves 13 are 25 opened.

Each suction valve 11 is provided with a stem 18 which is guided above the valve in a stationary sleeve 19, and which is continued a short distance below the valve by 30 a short pin 20. These pins of the suction valves are actuated, according to the invention, by a regulating member in the shape of a cam disk 21 which is adjustable by hand into different positions of regulation for 35 stepwise variation of the output of the pump, as well as by two governing members in the shape of cam disks 22 and 23, which are driven from the crank shaft 6 and serve positively to open the suction valves at the 40 beginning of the suction strokes of the corresponding plungers. When the plungers of the two cylinder groups are driven by two cranks 4 and 5 displaced 180 degrees with respect to each other, the two cam disks 22 45 and 23 are in accordance therewith displaced 180 degrees with respect to each other, see Fig. 2. The cam disks 22 and 23 actuate the suction valve pins 20 through the medium of push rods 24 and 25, respectively, 50 which are capable of sliding in the radial direction in brackets 26 projecting from the partition 9, and which rods carry rotatable rollers 27 and 28, respectively, at their inner ends, which rollers are adapted to be actuated by said two cam disks. At the outer ends of the push rods there are secured angular heads 29 and 30, respectively, which are adapted to actuate the pins 20 of the suction valves and to be actuated by the cam 55 disk 21 which for this purpose has its cams 31 of unequal lengths located under the laterally projecting arms of said heads.

The manually adjustable cam disk 21 is 60 secured to a shaft 32 one end of which is rotatably journalled in a projecting portion 33

of the partition 9, and the other end of which is journalled in a bearing 34, which is simultaneously a stuffing box, in the wall of the suction pipe connection 16. To the outer end of the shaft 32 a hand lever 35 is secured 70 which has a pointer 36 movable over a scale on a disk 37 secured to the pipe connection 16. Said scale is preferably graduated in such manner that it shows directly the various outputs of the pump obtained by adjusting the cam disk 21 into different positions. In order to lock the cam disk in such different positions the lever 35 is provided with a 75 sliding and spring-actuated handle 38 which may be made to engage different holes 39 in 80 the stationary disk 37. The two cam disks 22 and 23 driven from the crank shaft 6 are secured to a sleeve 40 which by the intermediary of a suitable bushing 41 is rotatably journalled on the above-mentioned projecting portion 33 of the partition 9. The sleeve 40 is provided with a row of teeth 42 with which meshes a gear wheel 43 on an intermediate shaft 44 which passes through 85 the partition 9 and carries, on the other side 90 of said partition, a second gear wheel 45 which engages a gear wheel 46 secured to the inner end of the crank shaft 6. The dimensions of the various gear wheels are so chosen that the sleeve 40 and the two cam disks 42 95 and 43 will rotate with the same speed and in the same direction as the crank shaft 6, and said two cam disks are shaped in such manner that the suction valves 11 will be positively opened at the beginning of the 100 suction strokes of the corresponding plungers, and will be closed—under the influence of their springs 12—at the ends of the suction strokes of the plungers.

By adjusting by hand the cam disk 21 105 with its cams 31 of unequal lengths and which are indicated in Fig. 2 in dotted and dashed lines, into different positions of regulation there is attained in a manner previously known the result that the suction 110 valves 11 of certain—various numbers of—cylinders 1 will be maintained permanently open, so that the corresponding cylinders do not take part in the pumping, a stepwise variation of the output of the pump being thus 115 attained. It is to be observed that the cams 31 are located below the heads 29 and 30 on the push rods 24 and 25 and actuate the pins 20 of the suction valves through the medium of said heads, so that, when certain 120 suction valves are maintained in raised position in this manner, also the rollers 27, 28 on the corresponding push rods are maintained in position raised from the cam disks 22, 23, so that they are not actuated by said 125 disks. In this manner unnecessary idle movement of the rods 24 and 25 is avoided. Those suction valves, on the other hand, which are not maintained permanently open in the manner described, but which take part 130

in the pumping—in the location of the cams 31 of the cam disk 21 indicated in Fig. 2 such is the case in respect of all twelve suction valves, so that the pump will thus operate to full capacity—are actuated through the medium of the push rods 24 and 25 by the two cam disks 22 and 23 in such manner that they are positively opened immediately at the beginning of the suction strokes of the 10 corresponding pump plungers. In this manner it is possible to select such strong springs 12 for actuating the suction valves that these suction valves will again be rapidly closed at the end of the suction strokes, so that no 15 part of the liquid once drawn in will pass back to the suction chamber 15, but the pump will actually give the exact desired output for which the cam disk 21 has been set. Owing to the positive opening of the 20 suction valves 11 the important advantage is also attained that it becomes possible to select the stroke and the dimensions of the suction valves as desired.

As shown in Fig. 1 both cam disks 22, 25 23 as well as the wheels 43, 45 driving said disks, and also the push rods 24, 25 driven by said cam disks, are all supported by the detachable partition 9. In this manner the advantage is attained that all these parts 30 may be mounted on said wall outside the pump casing and afterwards be simultaneously inserted in their correct places by securing the partition in its place.

The embodiment above described and 35 illustrated in the drawing is only to be regarded as an example, as it may obviously be modified in several ways in respect of its details, without departing from the principle of the invention. Thus it is possible, 40 for instance, to locate the pump cylinders in only one single group or, if desired, in more than two groups, when the number of cam disks 22, 23 should, of course, be changed correspondingly. Also the number of pump 45 cylinders in each group may naturally be altered as desired.

I claim:

1. In a multi-cylinder pump, compressor and the like, the combination of a number 50 of cylinders, each having a suction valve combined therewith, plungers movable in said cylinders, regulating means adjustable into different positions of regulation and adapted in such positions to cooperate with a different number of said suction valves to 55 maintain the same permanently open, and governing means connected with said plungers so as to be driven with a speed corresponding to the movement of said plungers and adapted to actuate such suction valves which are not maintained permanently open by said regulating means in such manner that said suction valves are positively opened 60 at the beginning of the suction strokes of the corresponding plungers.

2. A pump according to claim 1 in which said cylinders are arranged in a number of groups, the plungers of the cylinders of which are driven by a corresponding number of cranks on a crank shaft, and in which the 70 governing means consist of a number of rotatable cam disks corresponding to the number of cylinder groups, said disks being displaced in respect to one another in the same manner as said cranks and being connected 75 with said crank shaft in such manner as to rotate with the same speed as said crank shaft.

3. A pump according to claim 1 in which said governing means actuates said suction 80 valves through the medium of push rods having heads which are adapted to raise the suction valves and are also adapted to be actuated by the regulating means in such manner that the push rods corresponding to such suction valves as are maintained permanently open by said regulating means are also maintained raised up from said governing 85 means.

4. In a multi-cylinder pump, compressor 90 and the like, the combination of a number of cylinders, each having a suction valve combined therewith, plungers movable in said cylinders, push rods adapted to actuate said suction valves, regulating means adjustable into different positions of regulation and adapted in such positions to cooperate with a different number of said push rods so as to maintain the associated suction valves permanently open, governing means connected 100 with said plungers so as to be driven with a speed corresponding to the movement of said plungers and adapted to actuate such push rods which are not actuated by said regulating means in such manner that the 105 associated suction valves are positively opened at the beginning of the suction strokes of the corresponding plungers, and a partition supporting said push rods and said governing means and detachably mounted 110 in the pump casing.

5. In a multi-cylinder pump, compressor and the like, the combination of a number of cylinders, each having a suction valve combined therewith, said cylinders being arranged in a number of groups, plungers movable in said cylinders, a crank shaft having a number of cranks corresponding to the number of cylinder groups and operatively connected with said plungers, regulating 115 means adjustable into different positions of regulation and adapted in such positions to cooperate with a different number of said suction valves so as to maintain the same permanently open, governing means consisting of a number of rotatable cam disks corresponding to the number of cylinder groups, said cam disks being displaced in respect to one another in the same manner as said cranks on said crank shaft and being 120 125 130

connected with said crank shaft in such manner as to rotate with the same speed as said crank shaft, push rods adapted to actuate said suction valves, said cam disks being adapted to cooperate with said push rods so as to actuate such suction valves which are not maintained permanently open by said regulating means in such manner that said suction valves are positively opened at the

beginning of the suction strokes of the corresponding plungers, and said push rods being provided with heads adapted to be actuated by the regulating means in such manner that the push rods corresponding to such suction valves as are maintained permanently open by said regulating means are also maintained raised up from said cam disks.

JOSEF SVARTZ.
